UNITED STATES PATENT OFFICE.

JOHN SCOTT TULLOCH, OF CASHMERE, CHRISTCHURCH, NEW ZEALAND.

SHIELD FOR CYCLES.

1,169,888.

Specification of Letters Patent.

Patented Feb. 1, 1916.

Application filed July 15, 1914. Serial No. 851,074.

To all whom it may concern:

Be it known that I, JOHN SCOTT TULLOCH, a subject of the King of Great Britain, residing at 15 Woodbridge street, Cashmere, 5 Christchurch, in the Dominion of New Zealand, have invented new and useful Improvements in Shields for Cycles, of which the following is a specification.

This invention relates to an apron or 10 shield attachment for bicycles, tricycles, motorcycles and the like for protecting the rider from the weather and has more particular relation to shield attachments of the type comprising a covering adapted to 15 completely cover the handle bars and front part of the machine and to depend therefrom for a desired distance on either side, means being provided for securely holding the covering in the operative position.

20 The object of the present invention is to provide an improved covering of the above type which will serve as an efficient covering for the legs and lower portion of the body of the rider and be adapted when not 25 so required for use to be neatly rolled and carried upon the handle bars.

With this end in view the present invention consists in an apron or shield attachment comprising a covering adapted when 30 in the operative position to envelop the handle-bars and forward portion of the machine and when not required for use to be compactly rolled, and a frame work mounted upon the handle-bars and adapted to support the covering when in the operative 35 condition and to constitute a means of carrying such covering when in the rolled condition.

In order that the nature of the invention 40 and its construction may be fully understood reference will now be made to the accompanying sheet of drawings in which:—

Figure 1.— is a perspective sketch illustrating the use of the invention upon a motor cycle. Fig. 2.— is a perspective view of the handle-bars showing the invention in the rolled or closed condition thereon. Fig. 3.— is an underneath plan view of the upper portion of the device illustrating the frame-work employed for supporting it upon the 45 50

handle-bars. Fig. 4.— is a detail view of a portion of the forward end of the device showing an opening to receive the lamp-bracket of the machine, and, Fig. 5.— shows an alternative construction of such forward 55 end which is bifurcated and detachably connected together.

1 is a covering of any suitable material, such as textile fabric, leather, india rubber sheeting or the like which is draped across 60 the forward portion of the machine above the handle-bars 2, so that the central portion will lie approximately flat and incline upward toward the rear so as to deflect the wind and shed the rain while the two lateral 65 portions of such covering will hang downward for a desired distance on either side of the machine and constitute curtains to protect the legs of the rider and the central portion of the machine. For this purpose 70 the said central portion of the covering is supported at its rear portion by means of a framework of the desired width which frame is mounted upon the handle-bars at a sufficient height to give the necessary 75 clearance for the hands and any levers or other gear upon such handle-bars and also to provide the desired angle of inclination of such central portion of the covering as above mentioned. Toward its forward end 80 the said covering rests upon the handle-bars themselves and follows the general contour of such, while to secure it at its forward end the portion of such covering, extending beyond the front of the handle-bars, is so 85 formed as to lie or to be fastened together around the head of the machine, and is held in place by means of the ordinary lamp-bracket 3. Thus in one form of the invention such forward portion of the cover may 90 be suitably gored or darted to fit around the head and a suitable slot or opening 4 formed as shown in Fig. 4 to receive the lamp-bracket, while in another form such forward portion may be bifurcated or formed 95 with a vent 5 adapted to be secured together by means or dome or glove fasteners, buttons, straps, laces or other fastenings 6 so as to allow the lamp-bracket to project, as shown in Fig. 5. The remaining por- 100

tions of such material constituting the cover may be flat or suitably gored or darted so as to give fullness where desired and the said lateral or depending portions of such 5 are preferably secured to the foot-rests or other convenient portions of the machine by means of elastic straps or connections 7 or otherwise which, while serving to firmly hold such portions in place, will not impede the movements of the handle-bars. The 10 said framework, which may consist of spring-steel or other suitable material, may be of any suitable formation so as to support and give the required stiffness to the 15 rear central portion of the covering and permit of such portion being rolled up in the manner hereinafter described. By way of example therefore one construction of the frame is here shown but it must be understood 20 that the invention is not limited to such specific construction but includes within its scope any other means for supporting and stiffening the covering as required. As here shown, the said framework consists 25 of a member 8 which extends across at the desired height above the handle-bars 2 and to which it is attached by means of clips 9 formed in the bowed extremities of such member. The covering 1 is suitably attached 30 at the required point to the upper side of such member, while similarly attached to such covering, at or near its rear edge, is a second member 10 disposed approximately parallel with the member 8. The 35 said member 10 is supported and maintained in position by means of a pair of arms or spreaders 11 and 12 adapted to extend between such member and the member 8. For this purpose each of the said arms 40 is pivoted at one of its ends upon the underside of the member 8 as at 13 while the opposite or outer ends of such arms are formed with slots or bifurcations or other means 14 adapted to engage studs 15 provided upon 45 the underside of the member 10. By this arrangement, to place the device in the condition ready for use, the arms 11 and 12 are turned upon their said pivots so as to project outwardly from the member 8 in a 50 rearward direction and the said rear portion of the covering 1 stretched or extended sufficiently to permit of the bifurcations 14 engaging the studs 15 and so maintaining the member 10 and the adjacent portion of 55 the covering 1 in position. When not required for use however the device is adapted to be rolled up compactly and carried upon the handle-bars 2 by means of the member 8, as shown in Fig. 2. For this 60 purpose the arms 11 and 12 are disengaged from the studs 15 and turned upon their pivots 13 so as to lie parallel with the member 8, as indicated in Fig. 3. By now detaching the front portion from the lamp-

bracket and disconnecting the straps which 65 secure the side portions of the covering in place, such side portions may then be folded upon the central portion and the whole covering rolled up and secured by means of straps 16 or otherwise upon the member 8. 70

I claim:

1. An apron or shield attachment for bicycles, tricycles, motor-cycles and the like, comprising a support adapted to be secured to the handle bars thereof and disposed in 75 spaced relation above the same, said support including extensible portions adapted to project rearwardly therefrom and of said handle bars, and a cover connected to said support and adapted to extend over said rearwardly projecting portions, forwardly over the handle-bars and to depend at the side portions to protect the frame, drive mechanism of the machine and the rider. 80

2. A shield attachment for motor-cycles, 85 bicycles and the like, comprising a supporting member having means to connect the same to the handle-bars of said machine and straddling said handle bars in spaced relation to and above the latter, said supporting 90 member including foldable parts adapted to project rearwardly therefrom beyond the handle-bars and over the rider, a waterproof covering of flexible material secured to the supporting member and designed to 95 extend forwardly and rearwardly of the same over the handle-bars, in front of the frame of the machine and over the foldable portions respectively, means to anchor the covering at the front, said covering extending 100 downwardly at the sides, means for anchoring said downwardly extending sides and means for anchoring said foldable portions detachably to the covering.

3. An apron attachment for bicycles, 105 motor-cycles and the like, comprising a flexible covering adapted when in operative position to envelop the handle-bars and forward portion of the machine and to depend downward on either side, and a framework 110 detachably mounted upon the handle-bars adjacent to the grasping portions thereof, said framework comprising a supporting member having the end portions thereof curved to one side and in opposite directions 115 toward each other, means at the extremities of said curved portions to attach the same to the handle-bars with the supporting member extending across the latter, said covering being connected thereto, arms 120 pivoted to said supporting member and having notched end portions, a rigid member attached to the underside of the covering for disposition adjacent to the rider and having studs adapted for detachable engagement by 125 the notched end portions of the arms whereby to support the covering in a forwardly inclined position when in use, said arms be-

ing adapted when disengaged from the studs to be moved into alinement with the supporting member attached to the handle-bars and the covering being adapted to be folded and rolled to extend along the supporting member, and means for anchoring the covering in such condition.

In testimony whereof I have signed my name to this specification in the presence of two subscribing witnesses.

JOHN SCOTT TULLOCH.
